KANSAS.

DRYING AND AERATING MACHINE.

Application filed June 19, 1924. Serial No. 721,042.

This invention relates to an improved drying and aerating machine of the general character shown in Patent Number 1,202,445, issued October 24, 1916, to J. A. Sparks and 5 L. C. Waters, as well as a later Patent Number 1,278,593, issued September 10, 1918, to C. E. Clark, W. M. Clark and J. A. Sparks.

The invention seeks to provide a drying and aerating machine of the character indicated wherein, as compared with the patented structures, the blast of fresh air through the device will be greatly increased both in volume and velocity for thus effectually drying articles placed in the device and aerating said articles, and wherein novel means will be provided for accommodating the discharge of air from the device.

Other and incidental objects will appear hereinafter.

20 In the drawings:

Figure 1 is a sectional view showing a drying and aerating machine embodying the present invention,

25 Figure 2 is a horizontal sectional view on the line 2—2 of Figure 1, looking in the direction indicated by the arrows, and particularly showing the construction of the casing employed, and

30 Figure 3 is a top plan view of the basket particularly showing the turbine fan thereof.

In carrying the invention into effect, we employ a base 10 mounting a gear housing 11 at one end of which are spaced uprights

35 12. Associated with the gear housing are alined bearings 13 and 14 and journaled through said bearings is a vertical shaft 15 supported by a collar 16 coacting with the bearing 13 and by a beveled gear 17 coacting with the bearing 14. Journaled within

40 in the gear housing is a horizontal shaft 18 provided at one end with a beveled gear 19 meshing with the gear 17 and fixed upon the opposite end of said shaft is a pinion 20. Mounted upon the uprights 12 are alined

45 bearings 21 and journaled through said bearings is a shaft 22 to the outer end of which a hand crank or motor may be attached. The shaft carries a gear wheel 24 meshing with the pinion 20, so that, as will be seen, 50 the shaft may be turned for rotating the shaft 15.

Mounted upon the gear housing 11 is a casing 25, the peculiar construction of which constitutes one of the features of the present 55 invention. This casing includes a bottom

wall 26 which is appropriately secured to the housing 11 and is apertured and provided with an upstanding flange 27 to accommodate the upper end of the shaft 15 as well as the collar 16 and bearing 13. In 60 general contour, the casing is cylindrical and, as brought out in Figure 1, is of uniform diameter at its upper end. However, the side wall of the casing is spirally flared from the upper end of the casing to the 65 lower end thereof to produce an offset 28 at one side of the casing gradually widening from the upper end of the casing to the lower end thereof. The side wall of the casing is preferably formed from a single sheet 70 of material which, at its upper edge, is secured together at its ends while at its lower edge, the sheet is spirally bent about the axis of the flange 27 to produce the offset 28, when the overlapping ends of the sheet are 75 appropriately secured together from edge to edge of the sheet. At its lower edge, the side wall of the casing is preferably provided with a flange 29 which is appropriately secured to the bottom wall 26 and depending 80 from the bottom wall at the other end of the offset 28 therein is a discharge spout 30. Removably fitting in the upper end of the casing is a frusto-conical cover 31 provided axially with a depending fresh air inlet tube 85 or spout 32 and preferably equipped with a handle 33 extending over the outer end of said spout.

Mounted upon the upper end of the shaft 15 is a basket 34 to the bottom wall of which 90 is attached a spider 35 connecting the basket with the shaft. The side wall of the basket is provided with openings 36 and mounted upon said side wall near the upper end of the basket is a series of external fan blades 95 37 extending circumferentially of the basket and inclined downwardly with respect thereto. A further feature of the present invention lies in the provision, in connection with the basket, of a turbine suction fan. At the 100 upper end of the basket, the side wall thereof is flanged to accommodate a top plate or ring 38 suitably secured to the flange of the side wall and provided at its inner periphery with an upstanding annular flange 39. Integral with the flange 39 is an annular series of downwardly inclined radial fan blades 40 and fitting within the ring of fan blades is a ring 41 secured to the inner edges 105 of the blades and forming the mouth of the 110

basket. As will be observed, the blades 40 lie within the lines of the flange 39 and ring 41 so as to be protected thereby.

In use, the cleaned clothes or other articles 5 to be dried or aerated are placed within the basket 34, when the cover 31 is applied. Power is then applied to the shaft 22 for turning the shaft 15 and rotating the basket. As will be seen, any cleaning fluids retained 10 by the articles will be thrown by centrifugal force through the openings 34 of the basket into the casing to discharge through the spout 30. As the basket revolves, a blast of fresh air will, at the same time, be drawn 15 through the spout 32 by the turbine fan at the top of the basket to be impinged directly against the articles in the basket and discharged through the openings 36 when the air currents will be impelled downwardly by 20 the fan blades 37 toward the bottom of the casing and discharged through the spout 30. The articles in the basket will thus be effectively aerated and the odors of the cleaning fluids removed therefrom. Practical tests 25 have shown that by providing the turbine fan at the top of the basket, a large volume of air is drawn in through the spout 32 with appreciable force and it accordingly becomes necessary to form the casing 25 in such manner that the flow of air may freely discharge 30 at the bottom of the casing and thus be prevented from surging upwardly within the casing around the basket. The requirement is adequately met by the spiral formation of 35 the casing. In thus forming the casing, the diameter of the casing gradually increases toward the bottom thereof so as to accommodate the air currents forced toward the bottom of the casing while the offset 28 forms a 40 shoulder obstructing the currents of air against movement with the revolving basket and directing the air currents downwardly into and through the spout 30.

Having thus described the invention, what we claim is:

1. A drying and aerating machine including a casing provided in its bottom portion with a discharge opening, a perforated rotatable basket in the casing, an upstanding concentric flange on the top of the basket, a ring concentric with the flange and spaced inwardly therefrom, and a series of inclined fan blades fixed to and between said flange and said ring defining a turbine fan, means for admitting fresh air at the upper portion of the casing, and means for rotating the basket whereby said fan will be caused to induce a flow of fresh air downwardly through the basket to discharge at said opening. 45 50 55 60

2. A drying and aerating machine including a casing having a side wall vertical through a portion of its extent and inclined through the remainder of its extent whereby the lower edge of the wall will define a spiral offset while the upper edge thereof will define a circle, the end of the inclined portion of the wall overlapping the end of the vertical portion thereof and being secured thereto whereby to present an obstruction to 65 discharging air currents, the casing being provided in its bottom with a discharge opening between the adjacent ends of the vertical and inclined portions of the wall, a perforated basket rotatable in the casing, 70 means for admitting fresh air at the upper end of the casing, and means at the upper end of the basket for inducing a flow of fresh air downwardly through the basket to discharge at said opening in the bottom of 75 80 the casing.

In testimony whereof we affix our signatures.
